UNITED STATES PATENT OFFICE.

EDISON E. RANDALL, OF KANKAKEE, ILLINOIS, ASSIGNEE TO PARAMOUNT KNITTING COMPANY, OF CHICAGO, ILLINOIS, A CORPORATION OF ILLINOIS.

MACHINE FOR SEWING LOOPED FABRICS.

1,205,108.

Specification of Letters Patent.

Patented Nov. 14, 1916.

Application filed November 19, 1915. Serial No. 62,407.

To all whom it may concern:

Be it known that I, EDISON E. RANDALL, a citizen of the United States, residing at Kankakee, county of Kankakee, State of Illinois, have invented an Improvement in Machines for Sewing Looped Fabrics, of which the following description, in connection with the accompanying drawing, is a specification, like characters on the drawing representing like parts.

This invention relates to a machine for uniting or sewing together the edges of knit goods or looped fabrics and as herein illustrated is particularly designed for sewing together edges of such articles as stockings, as when the stocking is knit on a circular knitting machine beginning at the toe and the edges at the toe have to be united to complete the stocking. Machines of this general type and of various forms are well known. They comprise a bed or support, a stitch forming mechanism fixed with relation to the bed or support, and a movable work supporting member carrying a series of projecting impaling pins which move with the support past the stitch forming mechanism. In the form illustrated as a preferred embodiment of the invention this machine comprises a circular support or base, a rotating work supporting ring carrying a circular series of radially projecting impaling pins and a stitch forming mechanism, the instrumentalities of which operate over each impaling pin as it comes opposite the stitch forming mechanism. The edges of the knitted or looped fabric to be united have their meshes superimposed and placed on the impaling pins so that the needle passes therethrough and the stitching unites the fabrics. These machines employ stitch forming mechanisms handling either one or two threads and the more recent and improved type of machine handles two threads making what is known as a two-thread lock stitch.

One object of the invention is to provide a signal preferably of an audible character for indicating to the operative of the machine when a thread breaks or fails so that the machine may be stopped and the thread replaced. If a thread breaks or fails during the sewing operation and is unnoticed by

the operative then the stitch forming instrumentalities will continue their operations but placing no stitches in the fabrics, and the fabrics will be removed from the impaling pins without being united and usually without the operative being aware of that fact. Before the fabrics pass to the stitch forming mechanism the edges projecting above the impaling pins are trimmed off close to the impaling pins by a suitable mechanism so that when the fabrics are stitched together there will be no more material projecting beyond the stitched portion than is necessary for strength. Any fabrics, therefore, which are removed from the impaling pins without being stitched would nevertheless be trimmed off by the trimming mechanism and be in such a condition that they could not be replaced upon the impaling pins and again run past the stitch forming mechanism. This is because the fabrics are of such a character that if again replaced upon the impaling pins a considerable amount must be left projecting above the impaling pins and again trimmed off by trimming mechanism, which would alter the character of the articles and at best cause them to be condemned as "seconds." These conditions have rendered it not feasible to provide such a machine with means for automatically removing the work from the impaling pins after the fabrics have been stitched together because such mechanism would operate to remove all the work which comes within its field of action whether the fabrics had been stitched together or not.

Another object of the invention is therefore to provide a combination in such a machine of trimming mechanism to trim off the edges projecting above the impaling pins, stitch forming mechanism to unite the edges, a signal to indicate the breakage or failure of a thread, and means for automatically removing the work from the impaling pins. Such a combination is now feasible and greatly increases the efficiency and value of such a machine. If a thread breaks or fails the signal at once indicates that fact to the operative and the machine is stopped before the automatic mechanism operates to remove the work from the im-

2
paling pins. Thus no work is lost or reduced to the condition of "seconds."

These and other objects of the invention will more fully appear from the accompanying description and drawings and will be particularly pointed out in the appended claims.

In the drawings, Figure 1 is a top plan view of an ordinary type of machine for 10 sewing looped fabrics in which the impaling pins are arranged in a circular series, in which the stitch forming mechanism is of the two-thread type, and in which are embodied preferred forms of the present invention; Fig. 2 is a side elevation of a signal and its immediate operating mechanism embodying a preferred form of the invention for indicating the breakage or failure of either of the threads; Fig. 3 is a 15 view chiefly in vertical radial cross section of a means for automatically removing the work from the impaling pins and the immediately associated parts of the machine.

It is unnecessary to describe in detail a 20 machine for sewing looped fabrics of the type herein illustrated so far as its general features are concerned because it is of well known character. It is shown as comprising the standard or base 1 from which rises 25 and projects forwardly the overhanging arm 2. A vertical stud 3 at the outer end of the overhanging arm 2 carries fixed thereon the circular bed or support 4. The rotary impaling pin support 5 is mounted to rotate 30 on this bed and carries at its periphery secured thereto and radially projecting therefrom the circular series of impaling pins 6. The work to be united such as the two 35 knitted portions of the stocking is placed on the impaling pins with the meshes of the two parts superimposed and preferably one mesh being placed on each pin. The operative sits at the front of the machine placing the work upon the pins as it comes in front 40 of the operative and the work so placed travels in the direction of the arrow in 45 Fig. 1.

The main shaft 7 of the machine is supported in suitable bearings in the standard 50 1 and from it are operated the various instrumentalities of the machine. A pawl 8 operated by the main shaft serves through suitable mechanism to rotate the impaling pin support.

55 Trimming mechanism of well known type is illustrated at 9 and comprises a pair of scissor-like blades operating in a horizontal plane and close above the impaling pins. These blades may be operated from a suitable eccentric 10 on the main shaft. As the work impaled on the pins travels in the direction of the arrow the edges projecting above the impaling pins are sheared off by this trimming mechanism leaving only that 60 amount projecting which is sufficient to re-

ceive and hold the line of stitching and secure a union of the fabrics of proper strength.

Stitch forming mechanism is also mounted on the standard 1 and operated from the main shaft. The details of this mechanism 70 are unimportant to the present invention and it may be of any usual or desired type. As illustrated it is of the two-thread type, that is, it comprises instrumentalities such as the needle 11 and looper or second needle 12, 75 each of which handles and manipulates a separate thread which are passed through the work or interlooped in such a manner as to secure a two-thread stitch in and unite the edges of the fabrics projecting above the 80 impaling pins. The threads 13 and 14 pass from their respective supplies over suitable tension devices 15 and 16 respectively over suitable spring take up arms 17 and 18 respectively to the needle and looper, respectively.

The work after being trimmed passes on the impaling pins to the stitch forming mechanism and the edges are united thereby with a suitable line of stitching. If during the stitching operation either or both of the threads break or fail the stitching is, of course, not performed and the work passes the stitch forming mechanism without being united. If then it is removed from the impaling pins it cannot again be stitched for the reasons already set forth or if again stitched can only be used as "seconds". In this manner much valuable work is lost and time wasted.

100 This invention provides a signal so constructed and operating as to indicate to the operative the failure or breakage of either or both of the threads of the stitch forming mechanism. This signal may take various forms within the broad scope of this invention and may indicate in any suitable manner. As a preferred form of the invention an audible signal herein illustrated as a bell 19 is shown. This bell with its operating mechanism may conveniently be mounted upon a bracket 20 which bracket may be secured to the base of the machine as by being mounted at one end upon the stud 21 and having a lug 22 at its forward end resting on the overhanging arm 2. The stud 21 may be any suitable part of the machine and is herein shown as a stud in which guides for the threads are formed. The bracket 20 which is shown in side elevation 110 in Fig. 2 has secured to it at its forward end by the set screw 23 the bell 19. The bell may be operated by a suitable striker 24 shown as attached to a rocker 25 pivoted to the bracket at 26. A spring 27 attached at 115 its upper end to the bracket and at its lower end to the striker acts to throw the striker toward the bell. The striker is swung away from the bell in any suitable manner by some moving part of the machine and for

120

125

130

that purpose an adjustable wiper 28 is shown secured to the rear end of the rocker 25 and bearing against an eccentric 29 such, for example, as the eccentric strap of the feeding pawl 8.

In the construction illustrated a latch 30 is pivotally mounted above the rocker 25 and for that purpose may be mounted on the stud 21. The rocker 25 is shouldered at 31 and the latch is of such a length that when it rests upon the top of the shoulder the striker 24 is out of contact with the bell, but when it is swung forwardly away from the stop 32 on the bracket the shoulder 31 will ride up behind the latch and allow the spring 27 to throw the striker 24 against the bell and thus make an audible sound.

In this form of the invention the latch is normally in the position shown in Fig. 2 with the striker out of reach of the bell and upon the breakage or failure of either thread the latch is swung forwardly to allow the striker to sound the bell. This operation of the latch may be secured in any suitable manner but as herein illustrated is secured by providing the latch with a controller member shown as a transverse arm 33 projecting therefrom and extending directly over the take up springs 17 and 18. If the machine was of such a type as not to have the take up springs then some other instrumentality operated upon the failure or breakage of the thread would be made use of. The operation of this device is now apparent. If a thread running over a take up arm breaks that take up arm will spring upwardly striking the rod 33 rocking the latch forwardly from off the shoulder 31 and causing the striker 24 to sound the bell. Thus if either thread breaks the bell is sounded and the operative's attention directed to the fact that the work is not being stitched.

The force of the blow given the bell by the striker 24 may be varied by adjustment of a set screw 34 in a projection 35 from the bracket extending over the rocker 25.

Suitable means are also provided for automatically removing the work from the impaling pins after it has passed the stitch forming mechanism and as this mechanism is only involved in this invention in its combination with the trimming mechanism, stitch forming mechanism and signal it may take various forms. A simple and preferred form is shown as a curved metal plate 36 having its outward end beveled at 37 with the beveled end extending from the base past the outer end of the path of the impaling pins so that as the work comes against the beveled edge it will be pushed off thereby from the impaling pins. This plate is shown as held in place by a set screw 38 on a friction brake 39 such as is commonly employed in machines of this type and held in

radial position by the set screw 40 usually found in such friction brakes. A lever 41 fulcrumed at 42 has a wedge or cam shaped free end beneath the plate 36 and when swung between the plate 36 and the friction 70 brake 39 elevates the beveled end 37 above the path of the work so as to prevent the work from being removed from the impaling pins. This is a convenient means for the operative to actuate when the signal sounds 75 and thus insure the prevention of the removal of the work.

Having fully described my invention, what I claim as new and desire to secure by Letters Patent is:

1. A machine for sewing looped fabrics comprising a movable support with impaling pins thereon, trimming mechanism for trimming the edges of the impaled fabrics above the impaling pins, stitch forming 85 mechanism for uniting said edges, means for automatically removing the fabrics from the impaling pins after they have been carried thereby past the stitch forming mechanism, and means for indicating the failure of 90 thread in the stitch forming mechanism whereby the operative is enabled to prevent the removal of trimmed but unstitched fabrics from the impaling pins.

2. A machine for sewing looped fabrics 95 comprising a movable support with impaling pins thereon, trimming mechanism for trimming the edges of the impaled fabrics above the impaling pins, a two thread stitch forming mechanism for uniting said edges, 100 means for automatically removing the fabrics from the impaling pins after they have been carried thereby past the stitch forming mechanism, a signal, and means for causing the operation of the signal upon 105 the failure of a thread, whereby the operative is enabled to prevent the removal of trimmed but unstitched fabrics from the impaling pins.

3. A sewing machine comprising a two 110 thread stitch forming mechanism, a bell, a striker, means for operating the striker, a latch for restraining the operation of the said means, and means for releasing the latch upon the failure of either thread 115 whereby the bell is sounded to indicate the failure of either thread to the operative.

4. A sewing machine comprising a two thread stitch forming mechanism, a pair of spring take ups one for each of said threads, 120 a signal, a latch for preventing the operation of the signal, a controller member for said latch operated by either take up upon the failure of its thread to release the latch and cause the operation of the signal. 125

5. A sewing machine comprising a two thread stitch forming mechanism, a pair of spring take ups one for each of said threads, a signal, a latch for preventing the operation of the signal, a controller member for 130

said latch extending transversely of said take ups and struck by either upon the failure of its thread to release the latch and cause the operation of the signal.

16 of the signal, a controller member for said latch operated by the take up upon the failure of the thread to release the latch and cause the operation of the signal.

- 5 6. A sewing machine comprising a stitch forming mechanism, a spring take up, a signal, a latch for preventing the operation

In testimony whereof, I have signed my name to this specification:

EDISON E. RANDALL.
